COMBINATION STORM LOUVER AND AUTOMATIC BACK-DRAFT DAMPER
Arthur W. Nelson, 343 S. Dearborn St.,
Chicago, Ill. 60604
Filed Oct. 21, 1965, Ser. No. 499,214
3 Claims. (Cl. 98—119)

ABSTRACT OF THE DISCLOSURE

Pivoted damper blades are combined with stationary louver blades to serve as automatic closures against the entry of rain, even though driven by high winds, into a ventilator. The damper blades are mounted between spaced louvers in such manner as to form wind receiving pockets for maximum efficiency in automatically closing the damper blades.

This invention relates to a combination storm louver and automatic back-draft damper for a ventilator or the like and is particularly concerned with a combination of fixed louvers and freely pivoted movable louvers which may be opened by the pressure of air from an air conditioning apparatus or the like but which will automatically close against the entry of rain into the ventilator.

One object of the invention is to provide a plurality of stationary louver blades sloping downwardly and outwardly relative to a ventilator, and back-draft damper blades freely pivoted along their upper edges in the spaces between successive louvers.

Another object is to provide each damper blade pivoted adjacent the louver blade above it and arranged to slope downwardly and outwardly from the pivotal connection whereby gravity tends to close the lower edge of the damper blade against the stationary louver blade below it.

Another object is to provide the arrangement just referred to operable to permit opening of the damper blade by the flow of exhaust air from the ventilator, but whenever wind velocity or pressure exceeds the exhaust air velocity or pressure, closure of the back-draft damper blade is effected so that any rain driven by the wind will be stopped by the damper blade and drained downwardly and outwardly along that portion of the upper surface of the fixed louver blade which lies outwardly of the closed end of the damper blade.

Still another object is to provide each damper blade with a stop flange along its lower edge which is parallel to and engaged against the louver blade below it in the closed position of the damper blade to provide an effective sealing area against the entry of wind-driven rain into the ventilator.

A further object is to provide damper blades which have upper and lower planar portions arranged with their lower surfaces at obtuse angles relative to each other to increase the effectiveness of the closing action of the damper blade when acted upon by wind pressure.

With these and other objects in view, my invention consists in the construction, arrangement and combination of the various parts of my combination storm louver and automatic back-draft damper, whereby the objects above contemplated are attained, as hereinafter more fully set forth, pointed out in my claims and illustrated in detail on the accompanying drawing, wherein:

The figure illustrates a vertical cross sectional view through a ventilator with my combination storm louver and automatic back-draft damper construction applied thereto, several modified shapes of back-draft damper blades being illustrated.

On the accompanying drawing I have used the reference numeral 10 to indicate a ventilator shaft through which air is discharged from an air conditioning appa-

2

ratus or the like. At the upper end of the shaft 10 a series of stationary louver blades 12 is provided which may be arranged on all four sides of the shaft 10 for simultaneous discharge from all four sides of the exhaust air, or from two or three sides when wind pressure closes one or two of the sides. The louver blades 12 slope downwardly and outwardly from the ventilator shaft 10 and are spaced apart as illustrated. Each one is provided with the usual drip flange 14 along its outer edge.

Below the uppermost louver blades 12 I show substantially flat back-draft damper blades 16, each having a stop flange 18 along its lower edge substantially fitting against the louver blade below the damper blade. The upper edge of the damper blade is hinged as indicated at 20 for free pivotal movement.

At the right side of the figure the damper blade 16 is open due to the discharge of air from the air conditioning apparatus as indicated by arrows 22. The damper blade 16 and a second damper blade 16^a for the far side of the shaft 10 are also shown terminating between end walls 24 for the louvers 12 on that side of the shaft. The remaining damper blades for the far side of the shaft have been omitted.

Whenever wind velocity or pressure exceeds the exhaust air velocity or pressure, however, the damper blade 16 will automatically close as shown at the left side of the figure where the wind direction is indicated by arrows 26. The closed damper blade thereby forms a barrier for the wind and particularly for any rain carried by the wind which impinges the outer surface of the damper blade, runs down it and over the stop flange 18 and then on to that portion of the louver blade below the damper blade outwardly of the damper blade as indicated by arrows 28. I have found in actual practice that this arrangement prevents all possibility of rain being driven in through the combination storm louver and back-draft damper arrangement disclosed, thus eliminating the flooding of air conditioning apparatus, or any space connected with the shaft 10, in a very efficient manner.

I have found that the damper closing action of the damper blades may be increased if instead of flat damper blades such as shown at 16, humped shapes such as shown at 16^a, 16^b, 16^c and 16^d are used. These humped damper blades have upper and lower planar portions 30 and 32, their lower or inner surfaces being at obtuse angles relative to each other. The dimensions of the planar portions and the angles referred to may vary as illustrated by the four different shapes illustrated. At the right side of the figure open positions of the damper blades 16, 16^a, 16^b, 16^c and 16^d are illustrated and these open positions may vary with different relative pressures between the inside of the stack 10 and the atmosphere outside the ventilator, and with the encountering of different wind velocities, the damper blade in each case assuming a balanced position as between the pressures on its opposite surfaces. In some instances, the blades will be wide open such as indicated for the blades 16^a, 16^c and 16^d at the right side of the figure, two of the blades 16^b being shown, the upper one partially open and the lower one fully open.

All of the damper blades are preferably provided with the stop flanges 18 which may stop against the louver blade below the damper blade or against a vertical flange 34 at its upper inner edge as shown for the damper blades 16^c and 16^d at the left side of the figure. By having the stop flanges 18 parallel to and against the surfaces they engage, an area of effective seal against the entrance of driving rain is provided aided by the pressure of the wind against the outer surface of the damper blade, greater pressure producing more effective sealing action against greater wind-driven rain force.

Actual installations of my combination storm louver and automatic back-draft damper have proven very effective against the entry of rain into ventilators even when the rain is driven by high winds. The arrows 26 at the upper left corner of the figure illustrate how the wind impinges the outer surface of the damper blade 16 and is trapped in a pocket between the damper blade and the adjacent exposed surfaces of the fixed louvers 12. Similarly, the damper blades 16^a, 16^b, 16^c and 16^d are held in their closed positions by wind pressure which in the case of each different shape and dimensions of planar portions of the back-draft damper blade varies in effectiveness. The shape and dimensions may, accordingly, be varied to suit different requirements.

From the foregoing specification it is obvious that I have provided a simple arrangement of fixed and movable louver and back-draft damper blades effective to permit substantially free flow of exhaust air from a ventilator but prevent the entry of wind and rain on the windward side or sides of the ventilator.

Some changes may be made in the construction and arrangement of the parts of my combination storm louver and automatic back-draft damper without departing from the real spirit and purpose of my invention, and it is my intention to cover by my claims any modified forms of structure or use of mechanical equivalents which may reasonably be included within their scope.

I claim as my invention:

1. In a combination storm louver and automatic back-draft damper, a ventilator having stationary louver blades sloping downwardly and outwardly relative to said ventilator, and back-draft damper blades freely pivoted along their upper edges in the spaces between successive louver blades, each of said damper blades being pivoted adjacent

the under side of the louver blade above it and sloping downwardly and outwardly from the pivot with its lower edge closing against the louver blade below it, the closed position of the damper blade being maintained by external wind pressure acting in a pocket formed by said upper louver blade and the closed damper blade and acting over substantially the entire area of said damper blade, the lower edge of said damper blade being movable toward the louver blade above it as the damper blade is opened by internal exhaust pressure.

2. A combination storm louver and automatic back-draft damper according to claim 1 wherein each of said damper blades has a stop flange along its lower edge which is parallel to and engages flatwise against the louver blade below it in the closed position of the damper blade to effect a sealing area against the entry of wind-driven rain into said ventilator.

3. A combination storm louver and automatic back-draft damper according to claim 1 wherein each of said damper blades has an upper planar portion and a lower planar portion, said planar portions being arranged at an obtuse angle relative to each other.
